UNITED STATES PATENT OFFICE.

JULES L. SAGET, OF NEW ORLEANS, LOUISIANA.

LADDER CONSTRUCTION.

1,350,242.

Specification of Letters Patent. Patented Aug. 17, 1920.

Application filed March 16, 1918. Serial No. 222,944.

To all whom it may concern:

Be it known that I, JULES L. SAGET, a citizen of the United States, residing at New Orleans, in the parish of Orleans and 5 State of Louisiana, have invented new and useful Improvements in Ladder Construction, of which the following is a specification.

My present invention pertains to ladder 10 constructions; and it consists in a combination ladder—*i. e.*, a ladder capable of use as a self-supporting ladder for general purposes and also capable of use in emergencies as a fire ladder designed and adapted to be 15 propped against a building.

One of the objects of the invention is the provision of a ladder possessed of the capacities stated embodying a construction that is simple and strong and is susceptible 20 of being manipulated and adjustably fixed without the employment of skilled labor or tools of any description.

Another object of the invention is the provision of a combination ladder that is 25 adapted to be readily and compactly folded after use as a self-supporting ladder, and transported on a hose-wagon or other vehicle, and then expeditiously and easily converted into a fire ladder—that is, a ladder 30 of considerable length, made up of strongly connected sections and adapted to be propped against a building or otherwise maintained in substantially upright position. Manifestly my novel combination ladder char- 35 acterized as stated can be used to advantage in those districts where conditions are such as not to justify the maintenance of a hook and ladder truck.

With the foregoing in mind, the invention 40 will be fully understood from the following description and claim when the same are read in connection with the drawings, accompanying and forming part of this specification, in which:

Figure 1 is a broken side elevation illustrating the upper portion of a self-supporting ladder constructed in accordance with my invention; the said ladder being made 45 up of two sections adjustably fixed with respect to each other and braced against lateral movement or tendency to fall toward the sides.

Fig. 2 is a top plan of the same, showing the two side props.

Fig. 3 is a detail longitudinal vertical sec-

tion showing the ladder sections as adjustably fixed or locked in alined relation for use as a straight ladder, designed to be propped against a building or other support.

Fig. 4 is a detail side elevation showing the manner of connecting one of the ladder sections referred to to another section of ladder arranged in parallelism, with a view to providing a long ladder for fire purposes.

Fig. 5 is a detail longitudinal section of the same, showing the manner of connecting the said lapped or parallel sections and strongly supporting the upper section on the lower section.

Figs. 6 and 7 are transverse sections, taken in the planes indicated by the lines 6—6 and 7—7, respectively of Fig. 4, and showing the manner of holding the said sections together in lapped relation.

Fig. 8 is a broken elevation of one of the side props employed in the self-supporting ladder shown in Figs. 1 and 2.

Similar numerals of reference designate corresponding parts in all of the views of 80 the drawings.

I contemplate in practice employing two self supporting ladders such as shown in Figs. 1 and 2 for general use, and also contemplate combining the two when a long 85 straight ladder is to be provided, after the manner shown in Figs. 4 to 7, for fire purposes.

The said ladders of the self-supporting type are identical in construction and therefore a detail description of the one 90 shown in Figs. 1 and 2 will suffice to impart a definite understanding of both. The self-supporting ladder shown comprises sections

1 having flanges 2 thereon and also having conventional or other suitable rungs 3, 95 plates 4 fixed to the upper ends of the side bars of the sections 1, one plate at each side of each side bar, and having angular extensions 5 and also having key-holes 6, two in each plate, keys 7 connected through chains or other cables 8 with the ladder sections 1 so as to form permanent parts thereof and having bibs 9, turn-buckles 10 mounted at the outer sides of the side bars of the sections 1, links 11, preferably of 100 metal, having slots 12 for the passage of the turn-buckles 10, and also having angularly-disposed ears 13 in which are key-holes 14, and side props 15, Figs. 1, 2 and 8, having keys 16 at their upper ends and 110

prongs 17 at their lower ends, whereby they may be firmly fixed in the ground or upon any other surface.

With the ladder sections relatively arranged and adjustably fixed as shown in Figs. 1 and 2, a strong and safe self-supporting ladder is afforded. When, however, it is desired to convert the said self-supporting ladder into a comparatively long straight ladder, the same may be readily accomplished by detaching the links 11 and the props 15 from the ladder sections and then swinging the ladder sections into alignment, on the keys 7 shown in Fig. 2 as pinnacles, and then locking the ladder sections in the aligned relation, Fig. 3, by the other keys 7, one of which is shown pendent in Fig. 1. Manifestly the adjustment referred to may be quickly and easily accomplished without the employment of skilled labor or tools; and it will also be manifest that the conversion of the ladder from a comparatively long straight ladder back into a self-supporting ladder may be as readily effected.

The side bars of one of the ladder sections 1 shown in Figs. 1 and 2 are provided near the lower ends with metallic clips 20; the said side bars being shown in inverted position in Figs. 4 and 5. The side bars 1^a of one of the ladder sections comprised in the complementary self-supporting ladder are equipped with metallic clips 21; and the said clips 20 and 21 are adapted to straddle the flanges 2 of the two sections when the same are in the lapped relation shown in Figs. 4 to 7, and thereby strongly hold the sections together in said relation, the spaced relation of the clips 21 with the side 1^a being such as to permit the clips 20 to slide under the clips 21 for the removal of the section. It will also be noticed by comparison of Figs. 4 and 5 that the side bars of the ladder section 1^a are provided with swinging supports 21^a, of metal or other suitable material, and that each side bar is provided in its edge near its end with a recess or socket 22. Each of the said supports 21^a is pivoted at 23 to the inner side of the adjacent side bar, and is slotted at 24 to receive a limiting pin 25, and each is notched or provided at 26 with a hook to engage and bear on a rung of the other ladder section and thereby strongly support the ladder section 1^a on such other ladder

section. Each support 21^a is, moreover, provided with a portion 27 which is bent over the outer edge of the adjacent side bar and seated in the noteh, or socket 22 thereof, and is provided with a lateral extension forming a finger piece 28, whereby the support may be conveniently manipulated at the outer side of the side bar.

It will be gathered from the foregoing that two self-supporting ladders such as disclosed herein may be used to advantage for general purposes in the trades, and when an emergency arises each self-supporting ladder may be very quickly converted into a comparatively long straight ladder, see Fig. 3, and when a very long ladder is necessary, as in the event of fire, the two comparatively long straight ladders may be combined and joined together, after the manner shown in Figs. 4 to 7. It will also be gathered that the ladder sections of Figs. 1, 2 and 3 may when the ladder is not in use be folded to parallel relation so that the ladder will take up but little space, and consequently two of the said ladders and their appurtenances may be conveniently carried upon a hose wagon or other vehicle.

In addition to the practical advantages hereinbefore ascribed to my novel ladder construction, it will be noted that the said construction is simple, compact and strong, and that it embodies no delicate parts such as are likely to get out of order after a short period of use.

Having described my invention, what I claim and desire to secure by Letters Patent, is:

In a ladder, the combination of ladder sections hinged at their upper ends, turn keys arranged on the sides of the sections, links having slots formed on their ends that receive the keys of the sections and also having members secured to the center of the links, and ears formed on the lower end of said members and having apertures therein, and laterally extending props having ends adapted to enter said apertures.

In testimony whereof I have hereunto set my hand in presence of two subscribing witnesses.

JULES L. SAGET.
